UNITED STATES PATENT OFFICE

THOMAS PATTERSON, OF RUSH, ILLINOIS.

IMPROVEMENT IN PLOWS.

Specification forming part of Letters Patent No. 32,311, dated May 14, 1861.

To all whom it may concern:

Be it known that I, THOMAS PATTERSON, of Rush, in the county of Jo Daviess and State of Illinois, have invented a new and Improved Plow; and I do hereby declare that the following is a full, clear, and exact description thereof, reference being had to the accompanying drawings, making a part of this specification, in which—

Figure 1 is a longitudinal section through the improved machine, taken in the vertical plane indicated by red lines xx in Fig. 2. Fig. 2 is a top view of the machine.

Similar letters of reference indicate corresponding parts in both figures.

This invention is an improvement in operating turn-plowshares for very heavy or light plowing, wherein the plow is supported under a carriage and raised and depressed by the plowman while sitting on the carriage.

The invention consists in connecting and bracing the plow-body to a beam, which is suitably jointed to the front part of the axle-tree of the carriage, and which projects out a suitable distance in front of said axle-tree, said beam being connected near its front end by jointed straps to a lever which is arranged in a convenient position to be operated by the plowman, as will be hereinafter described, and also at its front end by a jointed arm and chains to a sliding cross-tree to which the team are attached, all as will be hereinafter fully explained.

To enable those skilled in the art to make and use my invention, I will proceed to describe its construction and operation.

A represents an axle-tree, carrying on its ends wheels B B', one of which, B', is somewhat smaller in diameter than the other, B, for the purpose of keeping the axle-tree nearly horizontal, while one of the wheels runs in the furrow and the other over the unplowed ground.

C is the driver's seat, which is mounted over axle A on springs C' C', and situated near the large wheel B.

D is the draft-pole, which is securely bolted to the axle-tree A, as near to the hub of wheel B as possible without touching this hub. Draft-pole D projects out a suitable distance from the front side of axle-tree A, and has a cross-tree, (bar,) D', attached to its some distance in advance of the wheel B, in such a manner that this cross-tree D' is allowed to slide back

and forth on the pole D, and at the same time to work on a central pivot, a, the ends of which pass into longitudinal slots in plates b b', the former of which is a guard for holding the tree D' down on the pole D. The draft-pole D is securely braced at its rear end to the axle-tree A by a strap, C.

Below the draft-pole D is a beam, E, which is securely pivoted at its rear end to the axle-tree A, directly under the pole D, and which proceeds out from the axle-tree beyond the wheel B. This beam being pivoted at one end, as before stated, its forward end can be moved up or down by a longitudinal lever, F, which is arranged on top of pole D, to which the front end of beam E is attached by two straps, d d, which are jointed at their ends to each side of the beam E, and also to the front end of lever F. Lever F has its fulcrum on post F', and its rear end or long arm can be fixed at any desired point to the post F'', both of which, post F' and post F'', are secured to and project up from the pole D alongside of the driver's seat C.

The plow-body G is constructed of a frame, e, to which the mold-board and share are securely bolted. This plow-body has no landside, but a fin or colter, h, is secured to the landside edge of the frame e, and projects up therefrom a suitable distance for making a vertical cut through the sod to facilitate the passage of the plow. The upper end of the frame e is bolted to the front end of movable beam E, and with the two brace rods g g the plow-body is securely fixed to this beam E in the relative position with wheel B shown in Figs. 1 and 2 of the drawings. This wheel B, it will be seen, will follow in the furrow made by the plow, and the smaller wheel, B', will run on the unplowed land, thus keeping the axle-tree in a horizontal position.

On the top of the beam E, near its front end, a short transverse bar, h, is pivoted, to the ends of which two chains, K K, are fastened. The other ends of chains K K are attached to hooks i i on the back part of the cross-tree, and on each side of the slotted guard-plate. These two chains K K can be shortened or lengthened at pleasure.

Now it will be seen that when the team is hitched to the cross-tree D', the chains K K being properly adjusted the draft of the team will be directly from the end of beam E, and

much of the strain on lever F occasioned by the downward tendency of the plow-body will be removed. The lever will not therefore require much labor on the part of the driver to operate it in regulating the depth of the plow or in raising the plow entirely from the ground.

Having thus described my invention, what I claim as new, and desire to secure by Letters Patent, is—

The plow-body G, secured to jointed beam

E, as described, in combination with straps d d, lever F, jointed bar h, chains K K, and jointed sliding cross-tree D', all arranged and combined with the wheels B B', axle A, and draft-pole D, as and for the purposes herein set forth.

THOMAS PATTERSON.
